Erwin Wheeler, Marshall
ATTORNEY,®

UNITED STATES PATENT OFFICE.

CHARLES O. MERCKEL, OF MILWAUKEE, WISCONSIN.

CLAMP.

Application filed April 4, 1921. Serial No. 458,289.

To all whom it may concern:

Be it known that I, CHARLES O. MERCKEL, a citizen of the United States, residing at Milwaukee, county of Milwaukee, and State 5 of Wisconsin, have invented new and useful Improvements in Clamps, of which the following is a specification.

This invention relates to clamps.

The objects of this invention are to provide a clamp which will secure a plurality of rods in any desired position of adjustment; which employs a single fastening means for simultaneously securing all of the rods in their adjusted position; and which is readily and easily adjustable.

Further objects are to provide a clamp which is of extremely light weight; which may be cheaply and readily manufactured; and which is very rigid and serviceable.

20 Embodiments of the invention are shown in the accompanying drawings, in which:

Fig. 1 shows the clamp applied to a dip net.

Fig. 2 is a plan view of the clamp showing 25 a fragment of the rods.

Fig. 3 is a sectional view on the line 3—3 of Fig. 2.

Fig. 4 shows a modified form of clamp.

The clamp is adapted to be used for any 30 purposes where it is desired to clamp a plurality of rods in relative positions of adjustment and it is obvious that it is readily applicable to a variety of uses, such for example, as holding parts of scaffolding, of 35 holding in adjusted position the various supporting rods in laboratory apparatus and in other similar uses, and in the embodiment chosen for illustration, it has been shown as applied to a dip net.

40 Figure 1 shows the device as it appears when used in connection with the dip net. In this form, a plurality of individual and distinct rods 1, 2, 3 and 4 are independently adjustably held by the clamp indicated generally at 5 and after the desired adjustment has been secured, the screen 6 is stretched between the ends of the rods and secured thereto by means of suitable loops 7.

The clamp comprises a rectangular body 8 50 which is open top and bottom and which is provided with an intermediate web 9. In the form shown, the side walls or rectangular portion 8 and the web 9 are formed as one integral structure and may be conveniently cast of any suitable metal. A plurality of holes 10 is provided thru the rec-

tangular portion and these holes are arranged in pairs, that is to say, a hole upon one side is in alignment with a hole upon the opposite side as may be seen from reference 60 to Figures 2 and 3. The upper portion of the rectangular walls is provided with eight holes as indicated so that the rods may be passed thru any pair of aligned holes. The lower portion of the rectangular 65 part of the clamp is provided with four holes, that is to say, two aligned pairs thru which the lower pair of rods 2 and 4 may be passed.

A single clamping means secures all of the 70 rods together and to the clamp body. This clamping means comprises a carriage bolt having an enlarged head 11, a portion 12 which may be squared if desired, and a threaded shank 13, the threaded shank passing thru a central opening in the web 9. A thumb nut engages the threaded shank upon the upper side of the flange 9 and is provided with a circular flange 14 and with wings 15. When this clamp is tightened, it 75 will be readily seen that the enlarged portion 11 engages the rods 2 and 4 while the flange 14 engages the rods 1 and 3, drawing such rods towards the center of the clamp and causing them to bind against the walls 80 of their corresponding supporting openings 10. It is to be noted that the squared portion 12 substantially fits between the rods 2 and 4 and thereby prevents the threaded shank 13 from rotating when the thumb nut 90 is rotated. In the form shown, the rods have been so arranged that they do not contact with the central web 9, but bind upon the walls of their corresponding openings 10 when engaged by the thumb nut or enlarged 95 head 11. It is found that this gives a very secure gripping effect and is advantageous in a number of cases. However, it may be found desirable to so proportion the clamp body proper that the rods may engage the 100 web 9 if so desired when drawn inwardly by the clamp.

Fig. 4 shows a modified form of clamp in which the same general mechanism is employed, the clamping means and rods being shown in a different position. In this form, an extension 16 projects from one corner of the clamp upwardly at a slight angle and has a threaded centrally arranged opening 17 adapted to receive the correspondingly threaded shank of a handle indicated at 18. A corresponding threaded

aperture 19 is formed in a boss 20 which projects from the opposite corner of the clamp. This aperture is adapted to receive the shank of a handle when it is desired 5 to have the handle extend vertically upwardly from the plane of the clamp. It is therefore obvious from this modified form that the clamp may be used in a manner described and that the handle may occupy 10 either of two positions, one extending upwardly vertically from the clamp, and the other extending at a slight upward inclination so that the device may operate successfully when used with either of two types 15 of nets. In addition to the manner of operation illustrated in Fig. 1, it may be found desirable when using the angularly inclined handle to provide a net which extends outwardly from the clamp as illustrated in Fig. 4. In this form, the rods 20 extend outwardly in pairs from two adjacent faces of the clamp and are fastened to the net indicated in dotted lines at 21 in any suitable manner by being passed 25 either thru the meshes of the net or thru hems as desired.

It will thus be seen that a clamp has been provided which will hold rods whether round or square in any desired position of 30 adjustment. It will also be seen that this clamp is extremely rigid, may be cheaply and readily manufactured, and may be as readily adjusted.

I claim:

35 1. A clamp including a walled fitting provided with symmetrically disposed openings in its sides, a bolt and nut of a size adapted to engage simultaneously members aligned with openings upon opposite sides of the 40 bolt, and means for positioning said bolt centrally within said fitting.

45 2. A clamp including an open ended receptacle provided with a transverse partition intermediate its ends and apertures symmetrically disposed in its walls upon either side of the partition, and a bolt and nut centrally mounted in said partition and arranged to confine the members thrust through the apertures of the receptacle.

50 3. A universal clamp comprising a walled body portion having a plurality of open-

ings formed thru the walls thereof, an integral connecting web joining said walls, a plurality of rods passing thru said openings upon opposite sides of said web, 55 a fastening means passing loosely thru substantially the central portion of said web and provided with enlarged ends having relative motion of adjustment towards and from each other, and adapted to bind upon 60 said rods, one end of said clamping means having a rectangular portion adapted to be positioned adjacent certain of said rods and to thereby prevent rotation of said portion. 65

4. A universal clamp comprising a rectangular body portion having openings arranged in aligned pairs, an integral web intermediate the upper and lower margins of said body portion, rods passing thru 70 said aligned openings and adapted to be positioned upon opposite sides of said integral web, and a single fastening means comprising a threaded shank having an enlarged head adapted to engage certain of 75 said rods upon one side of said web and having a wing nut engaging said threaded stem and having an enlarged portion engaging certain of said rods upon the other side of said web whereby when said wing 80 nut is rotated, the rods are clamped in adjusted position.

5. A clamp comprising a rectangular body portion provided with a plurality of pairs of aligned openings adjacent its upper and 85 lower margins, an integral web intermediate its upper and lower margins and provided with a substantially central opening, rods passing thru said aligned openings and a single fastening means adapted to 90 clamp said rods and comprising a threaded shank extending thru said integral web and having an enlarged headed lower portion provided with a squared part positioned adjacent certain of said rods upon 95 one side of said web, and a threaded wing nut engaging the threaded shank upon the opposite side of said web and provided with an enlarged portion adapted to engage certain of said rods upon the opposite side of 100 said web.

CHARLES O. MERCKEL.
